CONTAINER AND CLOSURE THEREFOR

William Martin Vogel, Jr., Mendham, N. J., assignor to Standard Container, Inc., Rockaway, N. J., a corporation of New Jersey

Application February 29, 1952, Serial No. 274,105

3 Claims. (Cl. 220—72)

1

My invention relates to a protective metal container and associated closure means for a sleeping bag which has special advantages for use in connection with a survival kit for military type, high speed aircraft.

Space in the pilot enclosure of high speed military type aircraft is at an absolute premium because of airframe design limitations, the multitude of operation mechanisms and equipment necessary for protection of the pilot. Indeed, restriction of available space is so great that there is very little flexibility for accommodating variations in physical stature from the arbitrary mean pilot size. Consequently, any variation in the size of equipment manufactured for use by the pilot may have a serious effect on the efficiency and comfort of the pilot.

One of the standard pieces of safety equipment for use in military aviation is a survival kit which includes a great many articles ranging from small articles such as fishing tackle to large and bulky articles such as a shovel, a collapsible carbine and a sleeping bag. Packing all of this diverse equipment in a manner economical of space and conformable to other equipment items has created a problem which has been handled in the past by enclosing the bulky sleeping bag in a protective metal container around which are packed the remaining articles to form a kit which is located at a point between the seat type parachute and the cushion upon which the pilot sits. It has been thought necessary to provide an oblong container of 6" x 9" x 6" for the sleeping bag to accommodate its bulk and to provide tolerance for variations in its size and shape when folded. The inflexible height of the container has proved disadvantageous in use, since it reduces the amount of available headroom for the pilot. Also the conventional double seamed construction does not allow for change of pressure at high altitudes so that the can tends to expand and produce the cockpit "squeeze" familiar to taller pilots. The bulk of the can is not justified by any useful function that it might serve beyond serving as a container for the sleeping bag. In addition, the effectiveness of the survival kit has been reduced by the nature of the tear-strip type openings for this metal container, since the keys are apt to be lost or broken in use.

I have now devised a metal container which by reason of its design is capable of containing the sleeping bag in the form of a shallow space saving pack and which by reason of its construction and that of the cooperating closure means provides sufficient flexibility in height adjusta-

2

bility to accommodate production line variations in packaging bulk. The container of my invention employs a shallow rectangular open top drawn shell of the approximate dimensional area of a seat-pack parachute, i. e., about 14" x 15". The height of the shell is sufficient to contain the packaged sleeping bag and preferably is about 2½ inches. The shell is slotted at different height levels near the upper edge of each of two opposite side walls. A closure plate, advantageously reinforced by diagonal embossings, co-operates with the slotted shell of the container to provide a firm but readily releasable closure means which is sufficiently flexible and sufficiently adjustable with respect to the height of the container's contents for maximum economy in space, compressibility in service and efficiency in packaging. In the closed position, a spring wire closure means is passed through one pair of slotted openings in the upper portion of one side wall of the container shell and is passed over the closure plate and through an oppositely disposed pair of slotted openings in the wall of the container shell. In its preferred form, my invention contemplates a container shell which has been slotted at different height levels to provide for variations in the height of the container contents. According to a particularly advantageous application of my invention, the closure plate is also designed to serve as a hand shovel and thus the container's top or closure plate is able to replace one of the essential bulky articles of the standard survival kit. For this purpose, the closure plate is provided with an elongated opening suitable for gripping with the hand. In construction, the container and closure plate are provided with rounded side corners and bottom edges.

My novel protective metal container provides many advantages over those of the prior art. The length and width of the container approximate those of a seat-pack parachute and allow for more compact packing of the evacuated protective plastic sleeve containing the sleeping bag. The 50 per cent reduction in height of my container creates valuable space in the pilot's enclosure and the flexibility in height adjustability provided by the slotted openings at different height levels of the container shell may create additional valuable space. The container assembly is readily opened by compressing and withdrawing the spring wire closure means and requires no extraneous opening devices. In addition, all three elements of the container assembly are useful to the pilot after the container has

been opened and no longer serves to protect the sleeping bag. For example, the container body is water tight and may be used as a water holder or kettle. The closure plate with its diagonal embossings and gripping handle may be used as a shovel and the spring wire closure means may satisfy a variety of needs. The rounded corners and bottom edges of the container assembly afford protection against bruises or cuts on the user's legs when landing from a parachute jump.

The metal container of my invention will now be described with reference to the accompanying drawing in which Figure 1 represents a plan view of the assembled container shell, closure plate, and spring wire closure means. Figure 2 represents a partial section of Figure 1 taken along line 2-2. Figure 3 shows the spring wire closure means in expanded position. Figure 4 represents a partial section of Figure 1 taken along line 4-4 and Figures 5 and 6 represent sections of the closure plate taken along lines 5-5 and 6-6 respectively.

Container shell 1, as shown in Figures 1, 2 and 4, is a rectangular open top draw can 14" x 15" x 2 $\frac{1}{2}$ " (all inside measurements) having $\frac{3}{16}$ " outside hemmed top edges 2. Shell 1 has rounded corners 3 and rounded bottom edges 4. The shell has pairs of slotted openings 5 about $\frac{9}{16}$ " by $\frac{3}{16}$ " centered respectively $\frac{3}{8}$ " and $\frac{7}{8}$ " from the top of the container shell and $4\frac{1}{2}$ " from the side walls in each of two opposite side walls of the shell. Container shell 1 is advantageously made from 135 pound commercial tin plate of 0.014" thickness.

Closure plate 6 of slightly smaller overall dimensional area than container shell 1 (13 $\frac{1}{2}$ " x 14 $\frac{1}{2}$ ") and having rounded corners to conform to those of the container shell is made from hot rolled carbon steel, pickled and oiled, of 0.031" thickness. Closure plate 6 is reinforced by diagonal embossings 7 shown in more detail in Figures 5 and 6. Closure plate 6 is also provided with an elongated opening 8 about 1 $\frac{3}{4}$ " by 5" centered mid-way between the side edges of the closure plate and about 2 $\frac{1}{2}$ " from the top thereof. Opening 8 also has about $\frac{1}{8}$ " hemmed edges 9. In order to provide a suitable handle, closure plate 6 is further provided with a $\frac{1}{4}$ " hemmed top edge about 7 $\frac{1}{2}$ " long centered mid-way between the sides of closure plate 6.

Spring wire closure means 11 is of U shape and has outwardly flared ends. It is made of 0.125" spring wire retinned for protection.

I claim:

1. A metal container which comprises a seamless open-top, shallow, rectangular shell, at least one pair of slotted openings in each of two opposite side walls of the shell, a closure plate of slightly smaller overall dimensional area than the container shell, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 15 2. A metal container which comprises a seamless open-top, shallow rectangular shell, at least one pair of slotted openings in each of two opposite side walls of the shell, a closure plate of slightly smaller overall dimensional area than the container shell, an elongated opening situated near the top of the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 20 3. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 25 4. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 30 5. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 35 6. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 40 7. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
- 45 8. A metal container which comprises a seamless open-top, shallow, rectangular shell having hemmed top edges, two pairs of slotted openings at varying height level near the top of each of two opposite side walls of the shell, a closure plate of slightly smaller overall dimensional area than the container shell, diagonal embossings on the closure plate, an elongated opening having hemmed edges situated near the hemmed top edge of and centrally located in the closure plate to provide a handle therefor, and a U-shaped spring wire equipped with outwardly flared ends which is capable of compression and extension inwardly through a pair of slotted openings in one side wall of the container shell across the upper surface of the closure plate and outwardly through a pair of slots in the opposite side wall of the container shell.
